(57) **CLAIM**

The ornamental design for an electric nasal aspirator, as shown and described.

DESCRIPTION

FIG. 1 is a top perspective view of an electric nasal aspirator, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a sectional view of part 9-9 of FIG. 3; and,

FIG. 10 is an enlarged detail view of area 10 in FIG. 9.

The broken lines in the drawings illustrate the portions of the electric nasal aspirator, which form no part of the claimed design.

The dash-dot-dash broken lines encircling the enlarged views are for annotative purposes only and form no part of the claim thereof.
